United States Patent Office

Des. 194,928
Patented Apr. 2, 1963

194,928

PLATE OR SIMILAR ARTICLE

Shigeru Masuda, Nagoya, Japan, assignor to Noritake
Co., Inc., New York, N.Y., a corporation of New York

Filed Mar. 13, 1961, Ser. No. 64,253

Term of patent 7 years

(Cl. D44—15)

The FIGURE is a plan view of a plate or similar article, showing my new design, a portion of the design being shown between dotted lines, and a repeat portion being shown between dot-and-dash lines.

The plate is of a conventional configuration when viewed from the side and bottom thereof.

I claim:

The ornamental design for a plate or similar article, substantially as shown and described.
